UNITED STATES PATENT OFFICE.

LYNN NELSON HITCHCOCK, OF SIOUX CITY, IOWA.

DESIGN FOR A CROCHET-NEEDLE.

53,591.

Specification for Design.

Patented July 15, 1919.

Application filed February 20, 1919. Serial No. 278,302. Term of patent 3½ years.

To all whom it may concern:

Be it known that LYNN N. HITCHCOCK, a citizen of the United States, residing at Sioux City, in the county of Woodbury and State of Iowa, has invented a certain new, original, and ornamental Design for a Crochet-Needle, of which the following is a specification, reference being had to the accompanying drawing, forming a part thereof.

The figure is a perspective view of a design for crochet needle, showing my new design.

I claim:

The ornamental design for a crochet needle, as shown.

In testimony whereof I hereunto affix my signature in the presence of two witnesses.

LYNN NELSON HITCHCOCK.

Witnesses:

MARIE McGINNIS,
ELLEN B. HOLLEY.
